W. FERDON

TOOTHPBRUSH

Filed June 13, 1923

UNITED STATES PATENT OFFICE.

WILLIAM FERDON, OF OMAHA, NEBRASKA.

TOOTHBRUSH.

Application filed June 13, 1923. Serial No. 645,156.

To all whom it may concern:

Be it known that I, WILLIAM FERDON, a citizen of the United States, residing at Omaha, in the county of Douglas, State of Nebraska, have invented certain new and useful Improvements in Toothbrushes, of which the following is a specification.

This invention relates to tooth brushes.

An object of the invention is to provide a tooth brush structure which will allow the bristles to be easily cleaned and maintained in a sanitary condition.

It is also an object of the invention to provide a structure which will enable the bristles to be closely inspected, and thereby to enable the user to ascertain if these bristles are in a clean and sanitary condition.

A further object of the invention is to provide a novel form of toothpick which may be incorporated in the structure of the tooth brush.

A still further object of the invention is to provide a folding form of tooth brush whereby to enable the brush to be made into an exceedingly compact article and thereby permit the same to be conveniently carried in the pocket of the user.

It is also an object of the invention that the foldable form of tooth brush be of such construction that the bristles will be protected and maintained in a sanitary condition when the brush is folded.

Other objects, and objects relating to details of construction, combination and arrangement of parts will hereinafter appear in the detailed description to follow.

The invention is illustrated by way of example in the accompanying drawings, in which:

Figure 1 is a perspective view illustrating the form of tooth brush embodying the present invention,

Figure 2 is a group view showing fragmentary portions of a tooth brush handle and bristle-supporting body together with the toothpick which serves as a coupling medium between these members,

Figure 3 is a plan view of the back of the body or bristle supporting portion of the brush and also showing in section a portion of the handle and the manner in which the handle is connected to the body of the brush by the tooth pick,

Figure 4 is a transverse sectional view taken through the body of the brush,

Figure 5 is a perspective view showing the foldable brush of this invention and with the brush extended with relation to the handle, and

Figure 6 is a perspective view showing the brush when folded and enclosed within the casing or receptacle carried by the handle.

Referring to the drawings in detail, and particularly to Figures 1 to 4, inclusive, 10 designates generally the body of the tooth brush or the bristle-supporting portion thereof which as shown comprises a frame substantially rectangular in shape and including the two side portions 11 which are integrally connected at their center and ends and the rear ends thereof extended in the form of a shank 12, said shank being provided at its outer end with a central threaded bore 13. Between the ends of the frame or body member 10 there is extended a plurality of laterally and materially spaced apart bristle-supporting strips 14, each strip being provided with a plurality of openings 15 adapted to receive bristles 16. The openings 15 are, of course, arranged longitudinally of the strips 14, as shown, and preferably these strips are tied together and also tied to the side members 11 of the body member or frame 10 by a cross web plate 17 at about the longitudinal center of the body member. Each side member 11 of the body or frame member 10 has its upper edge formed with an overhang rib 18, and each rib being arranged to define a guideway or groove 19. A cover plate 20 is provided which is preferably made of celluloid and which is adapted to slide within the groove or guideways 19. This cover plate is preferably transparent so that a person can observe the bristles therebeneath. It might be here mentioned that the cover plate 20 may have the name of the user of the toothbrush placed thereon and thereby to enable the user to at all times clearly identify his brush. Also if desired the name of the maker of the brush may be placed upon this slide.

A handle 21 is provided which may be of any desired construction and which is preferably formed at its outer end with an opening 22 for suspending the brush from a hook or nail. The other end of this handle as shown in Figure 2 is provided with an elongated bore 23, the outer end portion of

which is threaded, as at 24. A combined coupling member and a tooth pick is provided which comprises a stem which tapers toward its one end to provide a pointed portion 25 which may be utilized as a tooth pick and which has formed adjacent its other end the reversely threaded portions 26 and 27. The threaded portion 27 is adapted to engage the threaded bore in the 10 read end of the shank 12 formed upon the body or frame member 10, while the threaded portion 26 is adapted to engage with the threaded portion 24 of the bore 23 in the tooth brush handle, and in this way the handle 15 may be securely connected to the body or bristle-supporting frame 10 as illustrated in Figure 3.

It is believed from the foregoing description that the different advantages arising 20 from a tooth brush structure of this character will be clearly understood. It should, however, be pointed out that in case it is desired to clean the bristles the slide 20 may be removed and then water is forced 25 through the bristles 16 and in this manner the bristles may be thoroughly cleansed. This slide 20 is, of course, again positioned after the brush has been cleaned and the 30 inner ends of the bristles may at all times be viewed through this slide.

In case it is desired to use the tooth pick and the same should be disconnected from the body member or bristle supporting frame 10 and also the handle 21 then the 35 pick may be threadedly connected with the handle 21 and in this way a handle is provided for the pick.

Referring to Figures 5 and 6 the brush construction shown is the same as described 40 for Figures 1 to 4, inclusive, and similar reference numerals have been applied. The handle however in this construction comprises a section 28 which is preferably of the shape shown and which is provided with 45 a suitable elongated and threaded bore adapted to receive the pointed portion 25 of the tooth pick or coupling member and also adapted to threadedly engage the same and thereby connect the bristle supporting 50 frame 10 with the handle section 28. This handle section 28 has hinged, as at 29, to one end thereof an elongated plate 30, said plate being formed with a pair of side flanges 31 which are connected together at 55 their outer ends by an integral plate section 32, thus providing what may be referred to as a casing. Adjacent the upper edge and upon the inner side of each flange 31 there is provided a longitudinally extending 60 groove 33, whereby to provide guideways for receiving a slide or cover plate 34. Preferably this cover plate is provided at one end with a notch 35 to facilitate the removal thereof.

65 In the construction shown in Figures 5

and 6 the brush as a whole may be folded upon its hinge 29 so that the same will be disposed between the side flanges 31 and then the slide 34 may be moved to cover the brush as illustrated in Figure 6. It is obvious with a brush folded in this compact form the same may be readily positioned in the pocket of the user and at all times maintained in a clean and sanitary condition. It also might be pointed out that in the structure shown in Figures 5 and 6 the name 70 of the user may be placed upon the slide 24 or the name of the manufacturer may be placed upon this slide.

It is here to be particularly noted that 80 with a tooth brush body of the construction hereinbefore described the slide for the bristle-supporting frame may be removed and dental powder or paste inserted at the base of the bristles, that is, about the base 85 of the bristles, and then the slide again placed in position. With the dental powder or paste positioned in this manner the same will gradually feed or gravitate to the points 90 of the bristles when said bristles are moistened and the tooth brush being used for brushing the teeth. In this manner the dental paste or powder is economically used and this is especially true when comparing this 95 method for use of dental paste or powder with the usual method which is to place the powder upon the outer ends of the bristles. With the dental paste or powder on the ends 100 of the bristles a great part of the same is washed from the brush by dipping the same in water and in this way lost, whereas, by placing the paste or powder as heretofore recited the same is retained in the bristles and equally applied to the teeth of a person 105 using this particular structure of brush.

While I have shown and described the preferred form of my invention, I wish it to be understood that I am aware of the fact that the construction, combination and arrangement of parts may be changed by those 110 skilled in the art without departing from the spirit of the invention, as indicated by the appended claims.

I claim:

1. In a tooth brush, an elongated body 115 frame member laterally spaced apart bristle supporting strips extending longitudinally between the ends of the frame, and cross connecting strips, said strips provided with openings extending entirely therethrough 120 whereby to hold the inner ends of the bristle tufts, and leaving the ends of said bristles exposed, and a cover adapted to form a back for said brush.

2. In a tooth brush structure of the character described, an elongated frame, bristle-supporting strips extending between the ends of said frame and having apertures extending entirely therethrough, tufts of bristles mounted in said apertures, and a trans- 125 130

parent cover for said frame adapted to form a back for said brush structure and expose the ends of the bristles.

3. In a tooth brush structure of the character described, an elongated frame, bristle supporting strips positioned within the frame, said frame having each side portion provided with a rib and each rib having a groove upon its inner side, and a plate member 10 slidable in said grooves, for the purpose described.

4. In a tooth brush, a bristle-supporting

body member having a shank extending from its one end provided at its outer end with a threaded bore, a handle member having its inner end provided with a reversely threaded bore adapted to be brought into axial alignment with the bore in said shank of the bristle-supporting member, and a tooth pick having one end pointed and reversely threaded portions adjacent its opposite end, and adapted for threadedly connecting the handle to said shank. 15 20

WILLIAM FERDON.
